UNITED STATES PATENT OFFICE

1,954,515

MICROPHONE CASING

Adolph I. Blanc, Chicago, Ill.

Application December 3, 1931, Serial No. 578,623

1 Claim. (Cl. 179—179)

My invention relates in general to casings and more in particular to a casing for a hand microphone, and means for assembling same.

My invention is devised principally to house the mechanism for a small microphone, which would be carried about in the hand. Such a microphone has been adapted for connecting to a radio set for broadcasting through same, or adapted for ordinary broadcast using the microphone as a portable unit. In any event, it will be subjected to rough handling, is liable to be dropped, and in all must be of a very sturdy construction. In the interest of cost of construction and assembly, it is necessary to have as cheap a construction with as simple an assembly as possible.

An object of my invention is to provide a sturdy casing for a small hand microphone.

A further object is to provide a casing which will be inexpensive to construct.

And a further object is to provide a casing constructed in a manner that it will be simple to assemble.

Other objects and advantages will appear as my description progresses.

Referring now to the drawing,

Fig. 1 is a perspective of my casing assembled; Fig. 2 is a sectional view along line 2—2 of Fig.

1; and

Fig. 3 is a top plan view with the front and back portions of the casing slightly separated.

A casing for a small microphone is probably best constructed by casting or stamping same and I have devised my invention with a view toward adapting it to these methods. The casing 35 10 is constructed in two parts as shown particularly in Fig. 3, with a front cup-like portion 11 and back cup-like portion 12. The front cup 11 is formed integral with the base 13 on which it is mounted, while the back cup 12 is separate 40 from the base before it is assembled. Pegs 14 are cast on the inside of the front of the casing for mounting the microphone mechanism, principally a diaphragm, thereon, and an aperture 15 (Fig. 1) in the top of the assembled casing is provided through which a cut-out button may 45 protrude. Holes may be provided in the back portion or base through which the necessary wires may extend. An open grille 9 is provided in the face of the front cup.

As explained above, the front cup 11 is formed 50 integral with the base 13 at the neck 18. The back cup 12 has an annular flange 16 which fits into a corresponding recess 17 on the front cup of the casing. The front cup in turn has an outer 55 annular flange 19 which has a small lip or exten-

sion 21 fitting into a corresponding recess 22 in the annular flange 16 of the back cup. An aperture is provided in the lip 21 and a corresponding threaded aperture 23 is provided in the recessed portion 22 of the flange 16. A second threaded aperture 24 is provided in the lower edge of the flange 16. A hole 26 is bored through the base 13 and up through the neck 18.

In assembling my casing, the annular flange 16 fits into the recess 17 in the front cup 11, in a position such that lip 21 fits into the corresponding recess 22 on the flange 16 of the back cup. The cross-sectional view in Fig. 2 shows clearly the manner in which the front and back cups fit together. The two portions are held firmly in 70 position by means of a screw 27 inserted into the hole 26 and screwed into the threaded aperture 24 in the flange 16 of the back cup. Inasmuch as the front cup 11 is integral with the base 13, the front and back are thereby held firmly together at the bottom by means of the screw 27. The front and back are similarly held together at the top by a screw 28 inserted through the aperture 29 in the lip 21 and screwed into the threaded aperture 23 in the recess 22.

With my construction, I obtain a very sturdy microphone casing with a pleasing appearance, which may be assembled with a minimum number of operations.

Although I have described and illustrated the preferred embodiment of my invention, I do not wish to confine myself thereto, except as limited by the claim annexed hereto.

What I claim is new and desire to secure by Letters Patent of the United States is:

In a hand microphone, a base, and a casing for housing the mechanism mounted thereon, said casing comprising two cup-like sections, one of said cups including an annular recess, and the other of said cups including a corresponding annular flange, an annular abutting rim spaced inwardly from the outer edge of the flange having a recess extending through the rim, and a corresponding lip extending outwardly from the other cup adapted to fit in the recess, and means extending through the lip and recess to hold the cup-like sections together to form a continuous casing.

ADOLPH I. BLANC.
